MUFFLER CONNECTER

Arnold Haviland, Defiance, Ohio

Application April 16, 1937, Serial No. 137,312

7 Claims. (Cl. 285—183)

My invention has for its object to provide a muffler connector for connecting a muffler, of the type commonly used for muffling the exhaust pulsations of internal combustion engines, to the engine exhaust pipe and the muffler tail pipe. The invention provides a plurality of nested collars of different sizes, one or more of the nested parts being used according to the difference in size of the sleeve or neck of the muffler and the pipe to which it is to be connected.

As is well known, engines have different dimensional outlets and exhaust pipes of different sizes that are used to convey the exhaust products from the engine to the mufflers, while the mufflers have outlet sleeves or necks of certain sizes that often differ from the sizes of the pipes through which the exhaust gases are discharged. Where mufflers are injured and are to be replaced by new mufflers, it is necessary to provide mufflers having large inlets and outlets and provide a reducing connector to produce a sealing connection between the muffler and the exhaust and the tail pipe originally installed. By my invention, I have provided tightly interfitting expandable or contractible nested collars, having complete cylindrical intersealing parts and have located sets of the nested collars in the ends of the sleeves of the mufflers, whereby the mufflers may be installed and tight pipe fitting connection may be made upon removal of one or more of the inner sleeves.

The invention provides a muffler having sets of nested expandable collars located in the ends of the sleeves of the muffler, the collars of each set having diameters such that they may be tightly nested one within the other and the exterior collar having a dimension such as to interiorly fit the sleeve. When the muffler is to be connected to the exhaust and tail pipe, through which the exhaust gases pass, one or more of the inner collars may be removed according to the difference in the diameters of the exhaust and discharge pipes and the sleeves of the muffler so as to produce a tight fit between the connected parts. Preferably, a split clamping ring of the type well known in the art may be located about the inlet and outlet sleeves of the muffler to further secure the parts together.

The invention also provides a plurality of nested collars located in and fitting the muffler sleeve, the end edges of the collars being located substantially in the plane of the end of the muffler sleeve, the nested collars having interfitting recesses and projections to prevent inward displacement with respect to each other and the projec-

tions affording means for ready withdrawal of one or more of the inner collars to produce the desired tight fit about the exhaust or tail pipes.

The invention also provides nested collars which are slotted and which have continuous end edge parts. The portions intermediate the ends of the slots and the end edges of the collars are formed to readily flex and enable expansion of each of the sleeves and maintain elastic interfitting relation with respect to each other and with respect to the end sleeve of the muffler and also with respect to the ends of the exhaust or tail pipe.

To illustrate a practical application of the invention, I have selected a connector as an example of the various structures that contain the invention and shall describe the selected connector hereinafter, it being understood that the details of the connector may be varied without departing from the spirit of the invention. The particular connector selected is shown in the accompanying drawing.

Fig. 1 illustrates a perspective view of an end part of a muffler and the end of a pipe and the connector for producing interfitting of the end portion of the pipe and the muffler sleeve. Fig. 2 illustrates a view of a section of the connector, the pipe, and the sleeve shown in Fig. 1. Fig. 3 illustrates interfitting collars, one of which is partially withdrawn.

As shown in the drawing, the muffler 1 is provided at each end with a sleeve 2, one forming the gas inlet and the other the gas outlet. A plurality of nested collars are located in the sleeve. The pipes, such as the pipe 5, through which exhaust gases of the internal combustion engine are discharged, and the muffler tail pipe are located in the sleeves. The diameter of each sleeve is formed large enough to receive the larger of the pipes that are commercially installed and where the diameter of the outer surface of the pipe 5 is smaller than the sleeve 2, one or more of the inner nested collars 7, 8, and 10 are removed leaving in the sleeve the collar that will fit the pipe together with the outer of the collars to produce a sealed connection.

The collars are provided with slots 11 and are formed to have continuous end edge portions that close the ends of the slots. The end portions of the slots are formed Y-shape while the body portion of the slots extend parallel to the axes of the nested collars. The edge portions of the collars intermediate the arms of the parts that form the Y-shaped ends of the slots are recessed as at 12, preferably, to form V-shaped ex-

5
pansible edge portions 14 of the collars at the ends of the slots. The portions 14 form elastic portions that may be expanded or contracted without permanent deformation and thus provide an elastic fitting means for tightly fitting the contiguous collars. To render the sleeve 2 flexible, it may be split and a clamping ring 13 may be located on the sleeve to clamp the sleeve and the collars and the pipe.

10 The portions 15 of the collars intermediate the slots 11 are provided at their end edges with struck up parts to form protruding portions 17 that may be disposed in the V-shaped recesses 12 of the contiguous outer collars. Thus, the 15 collars may be telescoped relative to each other so as to locate the protruding portions 17 in the recesses 12 and their end edges in a common plane. Preferably but one end edge of each collar is provided with the protruding portions 17, whereby the inner collars may be removed and also whereby displacement of the nested collars with respect to the end of the sleeve 2 of the muffler will be prevented upon forcing the pipe into the inner of the collars.

20 25 Thus, by my invention, mufflers having nested collars located in the sleeves of the muffler may be furnished to automobile and truck owners or other individuals that desire to replace mufflers used in connection with internal combustion engines, and when it is desired to establish connection with the exhaust discharge pipes, one or more of the inner sleeves may be withdrawn depending on the diameter of the exhaust pipes that may be in use. In order to produce a tight 30 35 fit between the muffler and the parts of the exhaust discharge pipes, the pipes may be forced into the inner of the collars and the protruding portions will prevent entrance of the collars into the mufflers and thus enable an exceedingly tight 40 45 fit. Also, each of the collars being formed elastically expansible by the V-shaped edge portions of the collars formed at the ends of the slots, may be expanded to produce an exceedingly tight fit within the sleeve. If desired, the clamping ring 13 may also be fastened by means of a bolt and nut 18 to clamp and, if desired, contract the collars 10 to secure the pipe.

I claim:

50 1. In a muffler sleeve connector, a plurality of nested collars fitting the sleeve, each of the collars having slots extending parallel to the axes of the collars, and the opposite ends of each of the

slots closed by extendible sleeve portions and forming completely integrated slot edges.

2. In a muffler connector, a plurality of nested collars fitting the sleeve of the muffler, each of the collars having slots, the collars having end edge portions closing the ends of the slots, and the portions located intermediate the ends of the slots and the edges of the collars bent from the edges of the portions of the collars intermediate the slots to form collar expansible portions.

3. In a muffler sleeve connector, a plurality of nested collars fitting the sleeve, each of the collars having slots, and the collars having relatively slender end edge portions closing the ends of the slots and inwardly bent with respect to the slots to form integral collar expansible portions.

4. In a muffler connector, a plurality of nested collars, each of the collars having slots, the collars having end edge portions closing the ends of the slots, the portions located intermediate the ends of the slots and the edges of the collars bent from the edges of the portions of the collars intermediate the slots to form sleeve expansible portions, and one end of each of the collars having a projection substantially fitting the bent portions of the contiguous collar.

5. In a muffler sleeve connector, a plurality of nested collars fitting the sleeve, each of the collars having slots, the collars having bent end edge portions closing the ends of the slots and bent toward central parts of the slot to form integral collar expansible portions, and each of the sleeves having protruding portions fitting the outer edges of the said bent portions.

6. In a muffler sleeve connector, a plurality of nested collars fitting the sleeve, each of the collars having slots, the collars having recessed end edge portions closing the ends of the slots to form collar expansible portions, and the parts of the collars located intermediate the slots having at their end edges protruding portions fitting the recesses of the contiguous exterior collars.

7. In a muffler sleeve connector, a plurality of nested collars fitting the sleeve, each of the collars having slots, the collars having V-shaped end edge portions closing the ends of the slots to form collar expansible portions, and the parts of the collars located intermediate the slots having at their end edges protruding portions fitting the V-shaped recesses of the contiguous exterior collars.

ARNOLD HAVILAND.
